UNITED STATES PATENT OFFICE.

WILLIAM JOHN MANDLEY, OF SHELBURNE, ONTARIO, CANADA.

GRINDER.

995,071.

Specification of Letters Patent. Patented June 13, 1911.

Application filed November 12, 1910. Serial No. 592,071.

To all whom it may concern:

Be it known that I, WILLIAM JOHN MANDLEY, a subject of the King of Great Britain, and resident of Shelburne, in the county of 5 Dufferin, in the Province of Ontario, in the Dominion of Canada, have invented certain new and useful Improvements in Grinders; and I do hereby declare that the following is a full, clear, and exact description of the 10 same.

The invention relates to improvements in grinding machines, as described in the following specification and illustrated in the accompanying drawings that form part of 15 the same.

The invention consists essentially in the novel construction and arrangement of parts, whereby the tool support is movable longitudinally and laterally during grinding and the grinder suitably supported in 20 relation thereto.

The object of the invention is, to devise a simple and easily operated form of grinding machine, particularly adapted for the 25 grinding of cutter bars of agricultural machines, and which may be marketed at very low cost.

In the drawings, Figure 1 is a perspective view of the machine, showing one of the 30 supports for carrying the cutter blade to be ground, partly broken away. Fig. 2 is a perspective detail of a portion of the grinder, showing a slightly modified form of tool rest.

35 Like numerals of reference indicate corresponding parts in each figure.

Referring to the drawings, 1 is a rectangular frame having the legs 2 at each end thereof rigidly connected thereto and braced 40 by the bars 3.

4 are a pair of standards rigidly secured to the inner sides of the side members of the frame 1 and extending vertically above and below the said side members.

45 5 and 6 are blocks adjustably mounted on the upper and lower ends of the standards 7, said blocks having longitudinal slots 4, said blocks having longitudinal slots 7, therein through which the bolts 8 extend, said bolts being adapted to hold said slots 50 rigidly in their adjusted positions.

9 is a grooved wheel having its axle 10 journaled in the blocks 5.

11 are cranks connected to the ends of the axle 10 and operatively connected to the 55 treadles 12 by the connecting rods 13, said treadles being pivotally secured at their

outer ends to the inner sides of the rear legs 2.

14 is the grinder wheel shaft journaled in the bearings in the blocks 6 having a 60 grooved pulley 15 secured thereto over which the belt 16 extending around the wheel 9 extends.

17 is a seat secured at one end to the frame 1 for the operator to sit upon when working 65 the treadles 12.

18 are a pair of uprights rigidly secured to the outer sides of the frame 1 a short distance to the rear of the standards 4, said uprights having their upper ends formed 70 with right angular notches 19.

20 are metal straps secured to the forward edges of the uprights 18 and extending over the top thereof and bent downwardly at right angles and secured to the rear sides 75 and bent again outwardly from said uprights to an angular position and secured to the frame to form braces for said uprights.

21 and 22 are rollers journaled on suitable 80 pins extending across the rectangular orifices 23 formed between the straps 20 and the notched upper ends of the said uprights 18.

24 is a bar extending through the orifices 85 23 and engaging the rollers 21 and 22 and adapted to be moved laterally of the machine.

25 are vertical members secured to the 90 ends of the bar 24 and having their upper ends bent forwardly and formed eye shaped at their extremities.

26 are hook members having eye shaped upper ends secured in the eye shaped ends of the members 25 and depending therefrom, 95 said hook members being adapted to support the cutter bar 27 so that the said cutter bar may be swung backwardly and forwardly and laterally to be brought into engagement with the grinder wheel 28. 100

29 is a short tool rest adapted to be inserted between the pairs of rollers 21 and 22 and secured from longitudinal movement by the block 30. The rest 29 is adapted to be used when an ordinary circular 105 grinder wheel is used for grinding ordinary tools.

In the operation of this device, the operator sits upon the seat and operating the treadles 12 rotates the grinder wheel. The 110 cutter bar to be ground supported upon the hook ends of the hooks 26 and the operator

slides the bar 24 laterally to bring the first pair of teeth of the bar into line with the grinder wheel. The hook members 26 swing freely in any direction so that no accurate adjustment is necessary and as the vertical members 25 are the same length as also are the hooks 26, movement in either direction will hold the ends of the cutter bar in the same relative position, thereby insuring uniformity in the work accomplished.

What I claim as my invention is:—

1. In a grinder, the combination with a rigid frame, of a grinder wheel suitably supported from said frame, a pair of uprights extending rigidly from said frame and having lateral orifices therein, a bar extending across the machine and through said orifices and slideable therein, rigid uprights secured to the ends of said bar, and a tool supporting members suspended from said uprights and swinging freely thereon and supporting the tool to be ground above said grinder wheel.
2. In a grinder, the combination with a rigid frame, of a grinder wheel suitably supported from said frame, a pair of uprights rigidly secured to the sides of said frame to the rear of said grinder wheel, metal straps secured to the front and rear sides of the said uprights and forming a forwardly projecting loop, rollers arranged between the sides of said metal straps and

extending longitudinally above the machine, a rectangular shaped bar extending across the machine and between the pairs of rollers, vertically extending members projecting upwardly from the ends of said bar and having forwardly bent ends, and hook shaped members swinging from the extremities of said vertical members.

3. In a grinder, the combination with a rigid frame, of a pair of vertically arranged standards rigidly secured to the sides of said frame, bearing blocks adjustably secured to the ends of said standards, a grooved wheel rotatably supported in the lower bearing blocks, means for rotating said grooved wheel, a shaft rotatably supported in the upper bearing blocks, a grooved pulley fixedly secured to said shaft, a belt extending around said pulley and across the wheel, a grinder wheel secured to said shaft, a member extending across said frame and slideable in its supports, and tool supporting members supported from said bar and adapted to swing freely on their supports.

Signed at Shelburne Ontario this 24th day of October 1910.

WILLIAM JOHN MANDLEY.
